UNITED STATES PATENT OFFICE.

JOHN HIGHAM, OF LOS ANGELES, CALIFORNIA.

FOLDING OVEN.

Application filed November 29, 1920. Serial No. 426,965.

To all whom it may concern:

Be it known that I, JOHN HIGHAM, a citizen of the United States, residing at Los Angeles, in the county of Los Angeles and

5 State of California, have invented new and useful Improvements in Folding Ovens, of which the following is a specification.

This invention relates to a foldable oven 10 and an object thereof is to provide an oven which may be folded into a flat package so as to occupy a minimum space and which is especially applicable for use as a camp accessory and employed with camp stoves and 15 the like.

Another object is to provide a foldable oven so constructed as to be securely and rigidly held in its open position against possibility of being accidentally collapsed.

20 A further object is to provide an oven of the above character comprising few parts which may be readily assembled so as to enable the oven being built at comparatively small cost.

25 Other objects will appear hereinafter.

The invention is illustrated in the accompanying drawings, in which:—

Figure 1 is a perspective view of the oven as seen in its open position.

30 Figure 2 is a perspective view showing the manner of folding the oven.

Figure 3 is a plan view.

Figure 4 is a view in transverse section as seen on the line 4—4 of Figure 3.

35 Figure 5 is a view in longitudinal section as seen on the line 5—5 of Fig. 3.

Figure 6 is a horizontal section and plan view as seen on the line 6—6 of Figure 4.

40 Figure 7 is a detail showing modification of the means for tying the front portion of the sides of the oven together.

Figure 8 is a detail in cross section showing modified form of the oven bottom construction.

45 More specifically, 9 indicates the oven top which is rectangular in form and formed with downwardly extending flanges 10 on its opposite side edges and along its rear edge and hingedly connected to the inner faces of 50 the flanges 10 are side panels 11—12 and a back panel 13 each of which panels are adapted to be folded inwardly to extend substantially parallel with the top panel 9 or to be disposed in an open position substantially at right angles to the top panel; the flanges 10 serving as abutments to limit the

outward swinging movement of the panels 11—12 and 13 and to close the joint formed at the hinged connection of the panels to the top panel when the oven is in its open position, as shown in Figure 1.

The side panels 11—12 are formed at their rear ends with inturned flanges 14 against the inner faces of which the back panel 13 may be swung and which flanges 60 serve as abutments for the ends of the back panel and also act to close the joint between the end panel and the side panels when in their open position, as particularly shown in Figure 6.

70 As a means for fastening the side panels to the back panel in their open position to hold the side panels against spreading the side panels are formed with openings 15 adjacent the flanges 14 and 75 hooks 16 are mounted in the inner face of the back panel and arranged to be detachably engaged with the side panels by passing their hooked ends through the opening 15.

Hinged on the forward edge of the top 80 panel 9 is a door 17 which is adapted to be swung to lie against either side of the top panel and to depend from the top panel and extend between the forward ends of the side panels when the oven is in its open position 85 to close the oven or to be turned upwardly over the top of the oven to give access to the interior of the oven.

The oven is provided with a bottom wall 18 which may comprise a detachable panel 90 adapted to slidably engage the side panels 11 and 12 and to seat upon inturned flanges 19 formed on the lower edges of the latter as shown in Figures 1 to 6 inclusive or may comprise a pair of panels 20 and 21 hinged 95 at 22 on the lower edges of the side panels, as shown in Figure 8.

Formed on the inner faces of the side panels are flanges 23 forming a seat for a demountable shelf 24 here shown as comprising side frame members 25 and 26 connected together by cross bars 27.

The outer ends of the side frame members 25 and 26 are formed with hooks 28 and 29 adapted to extend astride of and engage the forward edges of the side panels 11 and 12, as particularly shown in Figure 6, to hold the forward portions of the side panels against spreading; the shelf thus serving as a tie and co-operating with the 110 hooks 16 on the back panel in holding the oven in its open position and which with the

bracing effect of the flanges 10 is overlapping the outer faces of the side panels serves to rigidly hold the oven in shape and insures against its being accidentally collapsed.

5 In some instances the tying together of the forward portion of the side panels may be effected by forming the slide bottom panel with hooks 30, as shown in Figure 7, which hooks are formed at the forward corners of the bottom plate and extend to the side thereof so as to be engageable with the forward edges of the side panels.

10 In folding the oven where the slide bottom panel is employed this panel and the shelf are removed and the hooks 16 are disengaged from the side panels whereupon the rear panel and the door may be swung inwardly against the inner wall of the top panel or the door swung outwardly and positioned over the outer face of the top panel. The side panels are then folded inwardly on the top panel, thus forming a substantially flat package.

15 The bottom panel and the shelf may then be positioned on the folded portion so that the entire oven will occupy but small space and may be conveniently packed for shipment or transportation, thus providing an oven which is admirably suited for use in 20 camping.

25 To prepare the oven for use the side panels are swung outwardly against the flanges 10 and the back panel is swung outwardly against the flanges 14 on the side 30 panel whereupon the hooks are engaged with the side panels, the bottom panel is positioned on the flanges 19 and the shelf is inserted in place with the hooks engaging the forward edges of the side panel.

35 40 In some instances the bottom panel may be dispensed with as where the oven is to

be employed on a covered stove or where the direct application of heat to the grid formed by the shelf is not objectionable, but in most cases the use of the bottom wall is desirable 45 to prevent flame or the products of combustion from entering the oven.

I claim:

1. In a foldable oven, a top panel having downturned flanges on its opposite side edges and on its rear edge, a side panel hinged on the inner side of each side flange, a back panel hinged to the inner side of the back flange, said side panels having inturned end flanges against the inner faces of which the back panel may abut, hooks on the back panel engageable with openings formed in the side panels, a shelf adapted to slide horizontally between the lower portions of the side panels, and fixed hooked members extending laterally from the forward corners of the shelf and engaging the forward edges of the side panels.

2. In a foldable oven, a top panel, hinged side panels thereon, a shelf, means for supporting said shelf on the side panels, said shelf being slideable longitudinally on said supporting means, and fixed hooked members extending laterally from the forward corners of said shelf adapted to be moved 65 in and out of engagement with the forward edges of the side panels on longitudinal movement of the shelf.

3. In a foldable oven, a top, side panels hinged to the top and extending downwardly, inturned flanges at the bottoms of the side panels, a bottom upon the flanges, and a shelf sliding between the side panels and having rigid hooks at its front corners to extend around the front edges of the side 75 80 panels.

JOHN HIGHAM.
